Thos. Brett.

United States Patent Office.

THOMAS BRETT, OF GENEVA, OHIO, ASSIGNOR TO HIMSELF AND W. H. SAXTON, OF SAME PLACE.

Letters Patent No. 76,883, dated April 21, 1868.

IMPROVEMENT IN RESTS FOR GRINDING HARVESTER-CUTTERS.

The Schedule referred to in these Letters Patent and making part of the same.

TO ALL WHOM IT MAY CONCERN:

Be it known that I, THOMAS BRETT, of Geneva, in the county of Ashtabula, and State of Ohio, have invented certain new and useful Improvements in Rest for Grinding Harvester-Cutters, &c.; and I do hereby declare that the following is a full and complete description of the same, reference being had to the accompanying drawings, making a part of this specification, in which—

Figure 1 is a side view of the rest.

Figure 2, a view of the top.

Figure 3, an end view.

Like letters of reference refer to like parts in the several views presented.

This implement consists of a pair of jaws, A, fig. 1, connected to a slotted stay or standard, B, fig. 3, by a short curving neck, C, and to which standard it is secured by a finger-screw, D, passing through the slot referred to, as shown in fig. 1, thus rendering the jaws on the standard adjustable.

The practical use of this implement is for holding the knives of a mowing-machine to the face of the grind-stone while they are being ground, so that a true and uniform edge and basil may be obtained to each section alike; also to assist in supporting the knives, and thereby relieve the grinder from sustaining the whole weight upon his hands, which, in grinding a whole range of knives, is usually very straining and tiresome to the arms.

The application of this implement to the purpose specified is as follows: A whole range, or a single section, is placed in the jaws, as shown in fig. 2, and secured therein by the finger-screw E. The edge of the knife is then brought to the face of the stone, the desired basil of which being gauged by the degree of the angle that the standard may be made to assume to the horizontal position of the sections; also the distance that the roller F may be from the screw D, and which roller is made to rest upon the stone and support the knives in any direction or position determined for the basil-angle. Thus the greater the distance that the roller may be from the screw D, or from the edge of the knife resting on the stone, or less the distance the standard may be turned in the direction of the dotted lines a, fig. 3, the more abrupt will be the basil-angle. On the contrary, the less the distance of the roller, or greater the distance of the standard in direction of the line referred to, the more acute will be the basil-angle; hence it will be evident that by the use of this rest, every section can be ground to an equal, uniform edge, and with but little wear to the grinder.

What I claim as my invention, and desire to secure by Letters Patent, is—

The adjustable standard B, and wheel F, as arranged in combination with the jaws A, for the purpose and in the manner as described.

THOS. BRETT.
